UNITED STATES PATENT OFFICE.

EUGENE C. LUDIN, OF NEW YORK, N. Y.

BOTTLE-HOLDER.

SPECIFICATION forming part of Letters Patent No. 703,802, dated July 1, 1902.

Application filed February 26, 1901. Serial No. 48,879. (No model.)

To all whom it may concern:

Be it known that I, EUGENE C. LUDIN, a citizen of the United States, and a resident of the city of New York, borough of Manhattan, in the county and State of New York, have invented a new and Improved Bottle-Holder, of which the following is a full, clear, and exact description.

The object of the invention is to provide a new and improved bottle-holder which is simple and durable in construction, cheap to manufacture, and arranged to securely support a bottle in an upright position.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a sectional side elevation of the same. Fig. 3 is a cross-section of the same, and Fig. 4 is an enlarged perspective view of the improvement with the cap shown removed from the shank of the base.

A suitably-shaped base A is formed with a hollow neck A', into which extend the middle portions of U-shaped arms B B', of which the middle portion of the arm B is formed with an offset B², in the under side of which fits the middle portion B³ of the other arm B', said arms B B' crossing each other at the middle portion at a right angle, the lower portions of the arms extending through registering openings A², formed in the neck A', as is plainly indicated in Fig. 4. A cap C fits over the neck A' and is provided with apertures C' in its depending flange C², said apertures registering with the apertures A² to permit the free passage of the arms B B'. The top B⁴ of the crossing portion B³ is preferably flattened, as shown in Figs. 2, 3, and 4, to fit against the under side of the cap C, so as to assist in holding the arms B B' in an approximately vertical position for the reception of the bottle, which latter rests with its lower end or

In order to lock the arms securely in place in the hollow shank A' and the cap C, molten metal D is poured into said shank and the hollow cap, when the base A and the arms B B' are held in an upside-down position, so that the molten metal upon hardening securely fastens the arms in position in the neck and cap and also secures the cap to the neck.

From the foregoing it is evident that the walls of the apertures A² and C' form supports for the arms B B' to prevent said arms losing their proper positions when the holder is used.

I do not limit myself to the use of but two U-shaped arms, as shown, as it is evident that more such arms crossing and interlocking each other in the neck of the base may be used, if desired.

Having thus fully described my invention, I claim as new and desire to secure by Letters Patent—

1. A bottle-holder, comprising a base, arms resting on the base and crossing each other at their middle portions, and a cap covering the crossed middle portions of the arms, the side portions of said arms rising from the base and cap.

2. A bottle-holder, comprising a base having a hollow neck, arms crossing each other at their middle portions in said hollow neck, a cap for closing the neck and middle portions of the arms, and metal filling said neck and cap and surrounding the crossed portions of the arms, as set forth.

3. A bottle-holder, comprising a base having a hollow neck, U-shaped arms crossing each other at their middle portions in said hollow neck, a cap for closing the neck, and metal filling said neck and cap and surrounding the crossed portions of said arms, as set forth.

4. A bottle-holder, comprising a base having a hollow neck, U-shaped arms crossing and interlocking each other at their middle portions in said hollow neck, a cap for closing the neck, and metal filling said neck and cap and surrounding the crossed and interlocked portions, as set forth.

5. A bottle-holder, comprising a base having a hollow neck, arms crossing each other at their middle portions in said hollow neck,

a cap for closing the neck and middle portions of the arms, and metal filling said neck and cap and surrounding the crossed portions of the arms, the arms extending through registering openings in the neck and the depending flange of the cap, as set forth.

In testimony whereof I have signed my

name to this specification in the presence of two subscribing witnesses.

EUGENE C. LUDIN.
